UNITED STATES PATENT OFFICE.

CHARLES STOOLFIRE, OF STILLWATER, OKLAHOMA TERRITORY, ASSIGNOR
TO HEMAN J. WHITTIER, OF KANSAS CITY, MISSOURI.

WIRE-STRETCHER AND WIRE-SPlicing TONGS.

SPECIFICATION forming part of Letters Patent No. 732,972, dated July 7, 1903.

Application filed August 23, 1901. Serial No. 73,036. (No model.)

To all whom it may concern:

Be it known that I, CHARLES STOOLFIRE, a citizen of the United States, residing at Stillwater, in the county of Payne and Territory of Oklahoma, have invented new and useful Improvements in Wire-Stretchers and Wire-Splicing Tongs, of which the following is a specification.

My invention relates to wire-stretching and wire-splicing tongs; and the object of my invention is to provide a means for bringing the free ends of two wires together and securing the same by a twisting splice when the opposite ends are secured in opposite directions.

Figure 1 is a side elevation of my invention, showing the position the wires are in before and after the splicing of the two ends. Fig. 2 is a perspective side elevation disclosing more clearly the position that the two wires are in before the splicing operation is accomplished. Fig. 3 is an inverted side elevation illustrating the opposite side of Fig. 1. Fig. 4 is a cross-sectional view taken on line X-X of Fig. 1, disclosing the position of a tusk which is secured to the lower jaw of the tongs, over which one end of the wire is passed before the splicing is produced. Fig. 5 is a cross-sectional view taken on line Y-Y of Fig. 1 through the lower jaw of the tongs and the position of a hollow tusk through which one end of the wire to be spliced is inserted. Fig. 6 is an inverted end view of the upper jaw of the tongs, showing the position of the two tusks secured to said jaw.

With the above description of the various illustrations of my invention I will now proceed to fully describe the same by referring to corresponding numerals on the drawings and specification, of which—

1 illustrates the lower jaw or member of my invention. 2 illustrates the upper jaw. These two are secured together in the usual manner, the lower member being provided with an elongated slot in the rear of the jaw of sufficient dimension to admit the shank or handle end of the upper jaw to pass through, being secured with a pivotal bolt 3, passing through each, the lower jaw being provided with a hollow tusk 4 and a solid tusk 7.

When the wires to be spliced are placed in a proper position for this purpose, end 10 of wire 5 is passed through said hollow tusk 4 and then turned or bent at right angles, 55 passing under tusk 6, which is secured to the upper jaw. It is then passed over and around tusk 7, (seen at Fig. 1,) said tusk being clearly illustrated at Fig. 4. The end 11 of the wire 8 is passed through an opening or eye 12 of the lower jaw, near the mouth thereof, which can readily be understood at Fig. 2. To hold this last-mentioned wire in the proper position while the splicing operation is being performed, I have provided a tusk 9, secured 60 to the lower jaw of the tongs, which will be readily understood by observing Fig. 3. This tusk is to prevent the wire from getting into a lateral or side position while the twisting is being done. When the wires are placed in 70 position as illustrated in Fig. 2, ends 5 and 8 (seen at Fig. 1) above the twist represent ends of the two wires coming from opposite directions before the free ends are spliced. The handles or shank ends of the tongs are 75 grasped, bringing the two jaws together tightly, gripping the wire 8 at the mouth of the tool, and securely kinking wire 5, as illustrated, with tusk 4, 6, and 7. When this is done, the position of the tongs, as illustrated 80 in Fig. 1, is reversed, and the handles or shank ends point in the opposite direction. By this reversal the slack in the two wires is taken up. When two or three turns or horizontal revolutions of the tool are made, the 85 free ends are made secure, as indicated in Fig. 1, and the tool removed.

Having now fully described my invention, what I claim as new, and desire to secure by Letters Patent of the United States, is— 90

1. A wire-stretching and wire-splicing tongs, comprising two members pivotally secured together, embodying an upper jaw and a lower jaw, adapted to open and close, a depending tusk integral with the rear of the 95 upper jaw on one side thereof, a depending tusk integral with the opposite side of said jaw near the front thereof, substantially as described.

2. A wire-stretching and a wire-splicing 100 tongs, comprising two members pivotally secured together, embodying an upper jaw and

a lower jaw, adapted to open and close, an upwardly-projecting hollow tusk integral with and near the front of the lower jaw, an upwardly-projecting solid tusk integral with said jaw and to the rear of said hollow tusk, an eye or opening 12 adapted to receive the end of the wire, substantially as described.

In testimony whereof I affix my signature in the presence of two witnesses.

CHARLES STOOLFIRE.
